UNITED STATES PATENT OFFICE.

EVERETT S. MINARD, OF FRESNO, CALIFORNIA.

CUT-OUT VALVE.

Application filed August 3, 1925. Serial No. 47,713.

My invention relates to a cutout valve, and more particularly to that form which is used to cut off a flow of fluid in which there is great pressure in the intake pipe 5 with which the cutout is connected which is transmitted to the interior of the valve.

Objects I have attained is the construction of a cutout valve of the character described, which is easy to operate, quick to 10 act, and which when opened gives an unobstructed passage for fluid between the intake and outlet openings.

I accomplish these and other objects hereinafter set forth by means of the device 15 hereinabove described and illustrated on the accompanying drawing, in which Figure 1 shows a sectional view of the valve, illustrating the throttle mechanism. Figure 2 is a fractional, sectional view of the housing 20 and showing the lever for turning the throttle and means for making fluid proof the opening through which the throttle passes. Figure 3 is a sectional view partly in plan of the device along the broken line 3—3 in 25 Figure 1. Figure 4 is a top view of the diaphragm.

In said drawing 7 is the valve body, or shell, having an intake opening 8 and an outlet opening 9. This shell is preferably 30 made tubular and is closed at both ends. The wall surrounding these openings is shown as threaded on the outside, although it can be threaded on either the outside or the inside as desired. The inside of the shell 35 forms a closed chamber with the exception of the intake and outlet openings. The throttle is shown as 10, and consists of a cylinder or tube 11, which has approximately the same bore as the outlet and inlet openings. The ends of tube 11 are curved to 40 conform to the inside periphery of the valve body or shell, but it should fit loosely, so that the fluid can readily flow between the ends of the cylinder or the tube 11 and the shell 7. To the tube 11 I have attached a 45 throttle shaft 21, which shaft extends through the shell 7 and has attached on the outside thereof a handle 20, said shaft handle and tube 11 being constructed and assembled so that by turning handle 20, the tube 11 can be turned within the housing 50 so that its open ends register with the intake and outlet openings, or it can be turned to other positions.

For the purpose of making air tight the bearing through which shaft 21 extends, I

have attached a rubber disc 22 to the shaft, so that the portion of the face near the periphery thereof will rest against the inside wall of the shell, around the opening 60 through which the shaft passes, as shown in Figure 2, said rubber disc acting as a check valve by the pressure of the fluid against the disc and the disc against the wall of the shell. 65

On the outside of tube 11 I have formed a flat surface and a boss on said flat surface for the purpose of attaching the diaphragm assembly. This diaphragm assembly is the active agent in obstructing or shutting off 70 the flow of the fluid through the outlet opening. The diaphragm assembly consists of a ring 14, which is curved on the top to conform to the inside wall of the shell 7 surrounding the outlet opening and makes a 75 water tight fit. This is shown in Figure 1. The under side 14^A of ring 14 is flat. I have formed a spring diaphragm 13, a top view of which is shown in Figure 4, the outside edge of the face being ground to a water 80 tight fit with the under face 14^A of ring 14. For the purpose of holding ring 14 and diaphragm 13 in position to make a fluid 85 tight fit, I have formed a flanged member 16, the flange being annular and of such size that it fits snugly within the opening in ring 14. Said flanged member has a depending annular extension 16^A, which extends downward around the boss 12. The diaphragm 13 has a hole in the center and 90 fits over the boss and is clamped in position thereon under ring 14 by the flanged member 16, the assembly being held together by a screw 17. A ring 23 around the throttle shaft is adapted to abut one face of the rubber disc 22. 95

In operating this valve, it will be noted that if a pressure of fluid is introduced into the shell or throttle valve body through intake 8, the fluid pressure is not against the 100 outside of the tube 11 only, because the fluid can pass between the ends of the cylinder and the walls of the valve body. The pressure on the inside and top of tube 11 will equalize the pressure on other portions 105 thereof, and the only pressure against the fitting part of the valve will be the pressure on the under side of ring 14, and the diaphragm 13.

By the reduction of the pressure as herein described, the throttle of the valve can 110 be turned more easily than otherwise.

This type of valve is especially valuable in connection with fire department apparatus and other apparatus where the pipes have great pressure therein. In some instances said pressure is 200 lbs. per square inch and in the form of valves now in use the friction created by such pressure makes the movement of the throttle a laborious act.

Having described my invention, I claim as new and ask for Letters Patent:

1. In a cutout valve the combination of a cylindrical chamber having an inlet and outlet opening between the ends of the shell, a throttle composed of a tube adapted to fit loosely within the cylindrical shell and pivoted therein in a position which permits the throttle to be swung so that the openings in the tube register with the intake and outlet openings, a closure for the outlet opening consisting of a ring adapted to surround the outlet opening, and positioned on the inside of the shell, and fitted therein, a diaphragm fitted on the inner side of the ring, and retaining means adapted to clamp the diaphragm to the outside portion of the tube.

2. In a cutout valve the combination of a chamber having an outlet and an inlet opening, a pivoted member within the shell operable by means extending through the shell, an annular ring adapted to fit around the outlet opening against the inside wall of the shell to form a fluid tight fit, retaining means for said ring attached to the pivoted member and adapted to hold the annular ring and pivoted member in constant relation and a diaphragm clamped to the pivoted member adapted to press against the under side of said annular ring, and thereby forming a fluid tight fit.

3. In a cutout valve the combination of a shell enclosing a chamber, an inlet opening and an outlet opening in said chamber, a pivoted member within the shell adapted to be positioned so there will be an unobstructed passage between the intake opening and the outlet opening, and means for cutting off the flow from the interior of the chamber to the outlet opening consisting of an annular ring fitted around the outlet opening so that the upper surface of the ring conforms to the wall surface of the chamber adjacent to the ring, a diaphragm attached to the pivoted member and positioned so that an annular portion of the face of the diaphragm will bear against the under face of the annular ring, retaining means to hold the pivoted member, diaphragm and annular ring in a constant relation to each other.

4. In a cutout valve, the combination of an enclosed chamber, having inlet and outlet openings, a pivoted member within the chamber adapted to be moved so that there will be an unobstructed passage between the outlet and intake openings, means for moving said pivoted member, and means for closing the outlet opening, consisting of an annular ring fitted on its upper surface to the inside wall of the shell around the outlet opening and surfaced to a plane on the under side, a diaphragm having an annular face adapted to fit against the plane surface on said annular ring, retaining means for holding the annular ring and diaphragm face in said relation to each other, and adapted to be moved with said pivoted member so that the outlet opening can be closed or opened at will.

EVERETT S. MINARD.
